(57) **CLAIM**

The ornamental design for a huber safety needle, as shown and described.

DESCRIPTION

FIG. 1 is a top perspective view of a huber safety needle showing my new design;

FIG. 2 is a top plan view of the huber safety needle of FIG. 1;

FIG. 3 is a bottom plan view of the huber safety needle of FIG. 1;

FIG. 4 is a front end view of the huber safety needle of FIG. 1;

FIG. 5 is a rear end view of the huber safety needle of FIG. 1;

FIG. 6 is a right side elevation view of the huber safety needle of FIG. 1;

FIG. 7 is a left side elevation view of the huber safety needle of FIG. 1;

FIG. 8 is a top perspective view of the huber safety needle of FIG. 1, showing an upper hub portion of the huber safety needle separated from a lower base portion of the huber safety needle;

FIG. 9 is a top plan view of the huber safety needle of FIG. 8;

FIG. 10 is a bottom plan view of the huber safety needle of FIG. 8;

FIG. 11 is a front end view of the huber safety needle of FIG. 8;

FIG. 12 is a rear end view of the huber safety needle of FIG. 8;

FIG. 13 is a right side elevation view of the huber safety needle of FIG. 8; and,

FIG. 14 is a left side elevation view of the huber safety needle of FIG. 8.

The broken line showing of parts of the drawings is included for the purpose of illustrating use and environment and forms no part of the claimed design.

1 Claim, 12 Drawing Sheets
